(57) **CLAIM**

The ornamental design for a faucet handle, as shown and described.

DESCRIPTION

FIG. 1 is a perspective view of faucet handle showing our design;

FIG. 2 is a side elevation view;

FIG. 3 is a top plan view; and,

FIG. 4 is a bottom plan view.

The broken-line disclosure in the view represents portions of the faucet handle in which the claimed design is embodied, but which forms no part of the claimed design.

1 Claim, 4 Drawing Sheets

FIG. 1

FIG. 2

FIG. 3

FIG. 4
